UNITED STATES PATENT OFFICE

STEPHEN F. BRIGGS, OF MILWAUKEE, WISCONSIN, ASSIGNOR TO BRIGGS & STRATTON CORPORATION, OF MILWAUKEE, WISCONSIN, A CORPORATION OF DELAWARE

LOCK

Application filed April 14, 1926. Serial No. 101,980.

Various types of locks have been designed and placed in use either for jointly or independently locking the transmission and ignition systems of automotive vehicles, and while these devices operate to deter the amateur from making unauthorized use of the car, the drivers frequently nullify the locking devices by leaving the keys in the locks, thus inviting the theft of their cars. It, therefore, is an object of this invention to provide an improved lock, which is so designed that the ignition system of the motor cannot be disrupted to stop the motor without first removing the key.

Another object of this invention resides in the provision of an improved device for simultaneously locking the transmission and motor ignition system having means whereby the key must first be removed before the device can be actuated to stop the motor and lock the transmission, thus affording protection against the unintentional leaving of the key in the lock by the operator.

It is another object of this invention to provide an improved device of the character described in which the lock dust cap or cover actuates means which prevent the manipulation of the device to disrupt the ignition circuit and lock the transmission while the key is in the lock, but instantly upon the removal of the key, the device may be moved to ignition and gear locking position.

And a further object of this invention resides in the provision of an improved device of the character described, wherein a key is first inserted in the lock to initially open the same and upon removal of the key the lock instantly moves to full open position, the lock being actuated to lock the transmission and disconnect the car ignition system with the key removed from the lock to thus preclude the leaving of the key in the lock by the driver.

With the above and other objects in view which will appear as the description proceeds, my invention resides in the novel construction, combination and arrangement of parts substantially as hereinafter described and more particularly defined by the appended claims, it being understood that such changes

in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a view, partly in section and partly in elevation, showing a gear shift lever mechanism equipped with a lock device embodying the principles of my invention;

Figure 2 is a view, partly in section and partly in elevation, taken through Figure 1 on the plane of the line 2-2 and illustrating the manner in which the lock is incorporated in the ignition circuit;

Figure 3 is a view looking down on the transmission cover on the plane of the line 3-3 of Figure 1;

Figure 4 is a fragmentary detailed view, partly in section and partly in elevation, illustrating the lock in its first or initial opening position prior to the removal of the key;

Figure 5 is a view taken transversely through Figure 4 on the plane of the line 5-5;

Figure 6 is a view similar to Figure 4 illustrating the lock after the removal of the key and its consequent movement to full open position;

Figure 7 is a fragmentary detailed view, partly in section and partly in elevation, illustrating the manner of connecting the locking cam with the dust cap or cover whereby the lock is prevented from full opening movement while the key is in place, and

Figure 8 is a view, partly in section and partly in top plan, taken through Figure 6 on the plane of the line 8-8 and illustrating a slightly modified construction.

Referring now more particularly to the accompanying drawings, in which like numerals designate like parts throughout the several views, 5 designates a bonnet portion formed on the cover 6 of a transmission housing 7 in which suitable gear devices, not shown, are mounted, the gear devices providing the change speed for the conventional

automotive vehicle and being operated selectively by means of two shifting rods 8 adapted to be selectively engaged by a gear shift lever 9 having a universal mounting in the bonnet 5 by means of a ball pivot 10. As is customary in constructions of this character, the inner end portion 11 of the gear shift lever is moved laterally with the transmission gears in neutral or non-working position to engage in one of the shifting devices 12 of the rod 8 so that a rearward or forward movement of the lever upper end will effect an opposite movement to the shifting device and the rod with which the end 11 of the lever is engaged.

The levers 8 are slidably journaled in bearings 13 formed in the cover 6 and have recesses or channels 14 formed therein adapted to register with a transverse bore or opening 15 in the cover 6 when the gearing is in neutral position to facilitate the engagement of two pin members 16 therein. The pin members 16 have their outer ends tapered and are adapted to be spread and consequently engaged with the rod recesses 14 by an actuating pin 17 slidably mounted in a bore 18 intersecting the bore 15, as best shown in Figures 1 and 2.

The actuating pin 17 is controlled by a lock device 19 mounted at a point convenient to the driver of the vehicle, which as illustrated in the drawings is in a boss or enlargement 20 formed as a continuation of the bonnet 5. The bore 18 is enlarged in diameter at its medial portion, as at 21, and at its extreme upper end is further enlarged in diameter in the boss 20 where it receives the locking device 19, as at 22, the shoulder 23 formed at the juncture between the bores 21 and 22 providing a rest or support for an insulating plate or disc 24 to be later described.

A locking barrel mounting head 25 is slidably mounted in the bore 22 and the actuating pin 17 is connected therewith so that movement of the locking barrel mounting head causes a similar movement to the pin 17. The head 25 is secured against rotation in the bore 22 but permitted a limited vertical movement by a guide pin or stud 26 extended into the bore 22 and engaging in a guide slot or opening 27 in the side of the mounting head, the vertical movement of the mounting head being limited to the length of the slot 27.

A locking pin 28 is transversely slidable in the lower portion of the lock barrel mounting head and is adapted to be projected from the side thereof to engage in a locking recess 29 in the wall of the bore 22. The locking pin 28 is extendable from and retractable into the head 25 by a lock plug 30 rotatably mounted in the head in a manner customary in constructions of this character. The plug 30 has the usual key receiving opening or

slot 31 in which a proper key 32 is adapted to be inserted to free the tumblers 30, see Figure 4, that normally secure the plug 30 against rotation with the locking pin 28 extended into its recess 29, locking the mounting head 70 in the position illustrated in Figure 1.

The insertion of the key 32 in the slot 31 aligns the tumblers, not shown, to permit the rotation of the plug 30, and rotation of the plug through approximately ninety degrees retracts the locking pin 28 into the mounting head freeing it from the locking recess 29 and permitting the head to move upwardly in the bore 22 carrying with it the actuating pin 17. As the locking pin is retracted from its recess the mounting head is instantly moved toward its outer position by an expansile spring 33 confined between the inner end of the mounting head and an insulating washer 34 secured over a pair of contacts 35 carried by the insulating member 24.

The contacts 35 are of the spring finger type and normally bear against the upper end portion of the actuating pin 17 on which a suitable insulator sleeve 36 is mounted, as best illustrated in figure 6, the lower portion of the insulator sleeve having a metallic ring or contact member 37 imbedded therein. When the mounting head is in its locked position illustrated in figures 1 and 2, the contact fingers engage with the insulating portion of the sleeve 36, and when the mounting head is moved to its unlocked or raised position, as illustrated in figure 6, the contact fingers ride onto the metallic ring 37 and are thus electrically bridged. Each contact finger 35 is connected with a terminal block 38, mounted below the floor boards 39 of the vehicle, by conductors 40, which are included in the ignition system of the motor which is indicated diagrammatically as at 41, so that with the mounting head 25 in its upper position the contact fingers 35 are bridged and the continuity of the electrical circuit of the ignition system is completed.

While a majority of the automotive vehicles are equipped with transmission locks of various types, the purpose of the locks is nullified either by the failure of the driver to lock the same when leaving the vehicle, or else by the careless leaving of the key in the lock. The carelessness of drivers invites the theft of cars and this invention provides means to make it essential that the transmission be locked before the ignition system of the car can be interrupted to stop the motor, and which is further designed to make it essential that the key be first removed from the lock before the ignition system can be rendered inoperative.

This is accomplished by providing an auxiliary locking means actuated from a dust cap or cover 42 pivotally mounted by a pin 43 and normally urged over the plug 30 by 130

a spring 44. The cover is fixed to the pin 43, as at 45, and the pin is rotatably mounted in the locking barrel mounting head, as best illustrated in Figures 4 to 7, the mounting head having a slot or opening 46 in register with the bore in which the pin 43 is mounted to receive a cam or tail locking piece 47 fixed to the pivot pin. The spring 44 normally urging the cover over the plug 30 tends to retain the cam 47 in its slot 46 inwardly of the peripheral surface of the mounting head. Movement of the dust cap or cover from its normal position over the plug 30 by the insertion of a key in the plug, projects the cam 47 outwardly of its recess 46 to engage in either of two recesses 48 and 49, to be later described.

The recesses 48 and 49 are formed in the wall of the bore 22 and receive the locking cam 47 when projected outwardly of its recess 46 and in alignment therewith, the recess 48 being located inwardly of the recess 49 and being of greater width. The width of the recess 48 is such that when the locking pin 28 is engaged in its recess 29 a movement of the dust cover to permit the insertion of the key in its slot will project the cam 47 outwardly to engage in the recess 48 adjacent its bottom or innermost portion and when the locking pin 28 is retracted from its recess the mounting head 25 moves outwardly under the force of the spring 33, a distance equal to the width of the recess 48. This initial opening movement of the mounting head is such that when the key 32 is withdrawn from its opening or slot and the cover 42 swings back to its normal position retracting the cam 47 into its recess 46, the locking pin 28 is freed of its recess 29 and the mounting head moved upwardly by the spring to its full uppermost position as defined by the lower portion of the guide slot 27.

With the mounting head in its uppermost position the recesses 46 and 49 are in register so that should the driver re-insert the key 32 in the plug the movement of the dust cap or cover 42 to free the key opening instantly engages cam 47 in the recess 49 and prevents the movement of the mounting head into its bore 22 to stop the motor and lock the transmission until the operator first withdraws the key. It will be thus apparent that the inadvertent leaving of the key in the lock is absolutely prevented by this construction.

Assuming the parts to be in their positions illustrated in Figures 1 and 2, the transmission is locked and the continuity of the motor ignition circuit interrupted, and before the motor can be started it is first necessary that the transmission lock be released and the contacts 35 be bridged by engagement with the contact ring 37. To accomplish this, the operator first inserts the key 32 in the slot 31, the dust cover moving the locking cam 47 out of its recess 46 against the spring 44 and

into the recess 48. The key is then rotated through approximately ninety degrees in a clockwise direction with reference to Figure 3 retracting the locking pin 28 from its recess 29, the energy of the spring 33 being released to move the mounting head upwardly. This initial movement of the mounting head is limited to the width of the opening or recess 48 by reason of the fact that the key 32 being in the lock the cover 42 is in its position illustrated by dotted line in Figure 5 and the locking cam 47 is engaged in the recess 48. In this position the transmission is still locked and the ignition system interrupted. The key 32 is then withdrawn from the slot 31, permitting the cover 42 to snap over the plug 30 under the action of its spring 44 disengaging the locking cam 47 from the recess 48 and permitting the further movement of the mounting head under the action of its spring 33 until the lower or bottom end of the slot 27 engages with the limit pin 26. At this point the recess 46 of the mounting head is in register with the recess 49 communicating with the bore 22 and should the key be reinserted in the lock, the cam 47 will be engaged in the recess 49 and the mounting head locked against movement to disconnect the motor ignition circuit until the key is withdrawn to thus prevent the inadvertent leaving of the key in the lock.

If desired, the recess 49 may be eliminated as illustrated in Figure 8, in which construction the dust cover is secured over the plug 30 while the ignition is on and the transmission unlocked. One of the rods 8 may also be provided with a recess or channel 14', see Figure 1, adapted to register with the adjacent bore 15 when in speed to permit the leaving of the vehicle in speed to serve as a brake, as is often customary.

In some instances it may be desirable to so construct the lock as to release the mechanical drive, at the same time retaining the ignition system closed. This may be accomplished by shortening the actuating pin member 17 so that when the lock proper has been moved to its initial unlocking position movement with the cam or tail piece 47 engaging the upper end of the recess 48 the locking pins 16 are free of the transmission rod recesses 14.

From the foregoing description taken in connection with the accompanying drawings, it will be readily evident to those skilled in the art to which an invention of the character described appertains, that I have provided a coincidental lock especially designed for use with automotive vehicles, which provides positive means of protection against the carelessness of drivers in leaving the key in the lock and thus inviting the theft of the car, and which is further designed to preclude the failure to lock the transmission in that the locking of the transmission is a pre-

requisite to the stopping of the motor as the ignition system is connected in with the transmission lock.

What I claim as my invention is:

1. A lock device, comprising locking means, an actuating member for the locking means and having a key receiving opening, and means carried by the actuating member and preventing the locking of the first means when a key is in the actuating member opening.

2. A lock device, comprising locking means, an actuating member for the locking means and having a key receiving opening, a cover movable over the actuating member to normally close the key opening therein, and means connected with the cover to prevent the locking of the first means with a key engaged with the first means.

3. A lock device, comprising locking means, an actuating member for the locking means and having a key receiving opening, a cover movable over the actuating member to normally close the key opening therein, and means operable by movement of the cover free of the key opening to prevent the locking of the first means.

4. A lock device, comprising a locking member, key controlled means for releasing the locking member for initial movement toward unlocked position, and means preventing the locking of said member with the actuating key engaged with the first means.

5. A lock device, comprising a stationary member having a bore therein, a key controlled locking barrel mounting head movable in the bore, a locking member connected with the mounting head, means limiting the movement of the mounting head, means normally urging the mounting head to one limit of movement, means for locking the mounting head at its other limit of movement against the urging means, key controlled means operable to release the locking means and permit movement of the mounting head to an intermediate position, means operable to lock the mounting head in its intermediate position as long as a key is engaged therewith, the last mentioned means being releasable upon the disengagement of the key from the mounting head and permitting the urging means to move the mounting head to the first mentioned limit of movement.

6. A lock device, comprising a stationary member having a bore therein, a key controlled locking barrel mounting head movable in the bore, a locking member connected with the mounting head, means limiting the movement of the mounting head, means normally urging the mounting head to one limit of movement, means for locking the mounting head at its other limit of movement against the urging means, key controlled means operable to release the locking means and the mounting head for movement to an

intermediate position, means operable to lock the mounting head in its intermediate position as long as a key is engaged therewith, the last mentioned means being releasable upon the disengagement of the key from the mounting head so that the urging means is free to move the mounting head to the first mentioned limit of movement, and said last mentioned locking means further securing the mounting head in its first mentioned limit of movement if a key is engaged with the mounting head while in said position.

7. In a lock device, an actuating member having an initial and final movement to one position and a single movement to its other position, means for locking the member in said other position, key actuated means for releasing said locking means and the actuating member for initial movement toward its first position, and means locking the actuating member at the end of its initial position until the key is withdrawn from the key actuated means, withdrawal of the key releasing the actuating member for continued movement to its first position, said actuating member being freely movable from its first position to its second position, said last mentioned means securing the actuating member in its first position in the event the key is reengaged with the key actuated means while the actuating member is in said position.

8. A device of the character described, comprising a bored stationary part, a locking barrel mounting head slidable in the bore of the stationary part, a lock plug having a key receiving opening and rotatably mounted in the mounting head, a locking pin transversally slidable in the mounting head and adapted to engage a locking recess in the bore of the stationary part when the head is at one position in the bore, the insertion of a key in the lock plug opening freeing the lock plug for rotation to withdraw the locking pin from its recess and release the mounting head for movement in the stationary part bore, said mounting head having an initial movement to an intermediate position upon the disengagement of the locking pin from its recess, means securing the mounting head in its intermediate position as long as the key remains in the lock plug opening, and means releasing the last mentioned locking means upon the withdrawal of the key to release the mounting head for continued movement beyond its intermediate position.

9. In a device of the character described, a lock adapted to be actuated by a key, an abutment preventing the fulfillment of the unlocking function of the lock until the key is removed, said abutment obstructing the locking function of the lock if the key is in the lock.

10. The combination with the ignition system of an internal combustion engine and a switch for controlling the same, of a key

controlled lock device for actuating the switch, means whereby the lock device is key released for initial movement closing the switch, means held against movement by the retention of the key in the lock device to secure the lock device in its intermediate position against completion of its movement to close the switch, the removal of the key from the lock device freeing the lock device for completion of its movement to close the switch, and means securing the lock device in its switch closing position upon the replacing of the key in the lock device.

11. A lock device, comprising locking means, an actuating member for the locking means having a key receiving opening, said actuating member being free for movement toward unlocked position upon its actuation by a proper key, means restraining said member from movement to full unlocked position at an intermediate point, and means operable by the withdrawal of the key from the actuating member to free said member for continued movement to unlocked position.

12. A lock device, comprising a locking means, a manually operable actuating member for the locking means and adapted to receive a controlling key, and means preventing manual movement of the locking means until the key is detached from the actuating member.

13. In an automotive vehicle, an ignition system and a mechanical drive, locking means for the mechanical drive, a switch within the ignition system and operable to connect and disconnect the system, means coordinating the mechanical drive lock and the ignition system switch, whereby the ignition system is rendered inoperable when the mechanical drive is locked, key released means for coordinating the operation of the mechanical drive lock and the ignition switch to unlock the mechanical drive and close the switch, said key released means being manually operable to lock the mechanical drive and open the ignition system switch, and means preventing the locking of the mechanical drive and the opening of the ignition system switch as long as a key is engaged with the key released means.

14. The combination with the ignition system of an internal combustion engine and a switch therein including a stationary contact of a movably mounted lock device adapted to receive a key to control the same, a movable contact carried by the lock device whereby movement of the lock device engages and disengages the contacts, and means contained within the key controlled lock device and operable to secure the same against movement to prevent the operation of the switch to render the ignition system inoperable as long as a key is in place in the lock device.

15. In an automotive vehicle, including an ignition system, and a control mechanism,

locking means for the mechanism, a switch within the ignition system and operable to connect and disconnect the system, means co-ordinating the mechanism lock and the ignition system switch, whereby the ignition system is rendered inoperable when the mechanism is locked, means adapted to receive a key for controlling the same and actuating the mechanism lock and the ignition switch to an intermediate position short of the position of the switch, means unlocking the mechanical drive and closing the switch, means freeing the key controlled means for continued movement from its intermediate position to unlock the mechanism and close the switch upon the withdrawal of the key from the key controlled means while in intermediate position, and means preventing the locking of the mechanism and the opening of the ignition system switch as long as a key is engaged with the key controlled means.

16. In an automotive vehicle including a mechanical mechanism and an ignition switch, a coincidental lock device therefor, comprising locking means, an actuating member for the locking means and having an opening adapted to receive an actuating key, means controlled from said actuating member for locking and unlocking the mechanical mechanism and opening and closing the ignition switch, an obstruction to the full unlocking of the mechanism and closing of the switch, means operable by the removal of the key from the actuating member to remove said obstruction, and means operable upon the insertion of the key in the actuating member while in unlocked position to obstruct the movement of the mechanism to locked position.

17. A lock device, comprising a bored stationary part having two locking recesses communicating with the bore, a lock cylinder mounting head longitudinally slidable in the bore, a locking pin transversely slidably in the head and engageable in one locking recess when the mounting head is at one limit of movement, key controlled means carried by the mounting head for actuating the locking pin, a lock cylinder dust cover normally disposed over the mounting head, a rod journaled in the mounting head and having the cover fixed to its outer end, a locking piece fixed to the inner end of said rod and normally retracted to lie within the body of the mounting head when the cover is disposed over the mounting head outer face, the locking piece being engaged with the other locking recess upon the movement of the cover to permit the insertion of a proper key in the mounting head, said other recess being of a greater depth than the thickness of the locking piece to permit a limited movement of the mounting head toward its other limit of movement with the locking piece therein, and means moving the cover over the mount-

ing head upon removal of the key to retract the locking piece within the body of the mounting head and free the mounting head for continued movement to full other limit of movement.

5 In testimony whereof I hereunto affix my signature.

STEPHEN F. BRIGGS.
